Des. 210,879
Patented Apr. 30, 1968

210,879

DENTAL JET CLEANSING UNIT OR THE LIKE

Robert N. Freedman, Great Neck, N.Y., assignor to Endura Appliance Corporation, Freeport, N.Y., a corporation of New York

Filed Mar. 28, 1967, Ser. No. 6,413

Term of patent 14 years

(Cl. D24—1)

FIG. 2

FIG. 1

FIG. 1 is a perspective view of a dental jet cleansing unit or the like showing my new design in the closed position;

FIG. 2 is a top plan view of the unit in the open position;

FIG. 3 is a front elevational view thereof;

FIG. 4 is a side elevational view thereof;

FIG. 5 is a rear elevational view thereof; and

FIG. 6 is a top plan view of the lower portion of the unit.

What is claimed is:

The ornamental design for a dental jet cleansing unit or the like, as shown.
